DESIGN FOR A SHOE

Ferdinand W. Ellington, Jamaica, N. Y., assignor
to Delman, Inc., New York, N. Y.

Application February 14, 1935, Serial No. 55,405

Term of patent 3½ years

To all whom it may concern:

Be it known that I, Ferdinand W. Ellington, a citizen of the United States, and resident of Jamaica, in the county of Queens and State of New York, have invented a new, original, and ornamental Design for Shoes, of which the following is a specification, reference being had to the accompanying drawing, forming part thereof.

Figure 1 is a plan view, and Figure 2 is a perspective view of a shoe showing my new design.

The dominant features of my invention of design comprise the decorative pattern defined by inlay over the toe and vamp portions of the shoe, as shown.

I claim:

The ornamental design for a shoe as shown and described.

Dated February 8th, 1935.

FERDINAND W. ELLINGTON.
